DISTORTIONLESS RADIO-FREQUENCY
AMPLIFIER

James D. Booth, Catonsville, Md., assignor to
Westinghouse Electric Corporation, East Pitts-
burgh, Pa., a corporation of Pennsylvania

Application January 6, 1942, Serial No. 425,766

7 Claims. (Cl. 179—171)

My invention relates to radio frequency amplifiers and, in particular, relates to circuit connections for radio frequency amplifiers employing remote cut-off tubes.

In radio frequency amplifiers employing remote cut-off tubes under normal operating conditions, it is found when plotting the gain curve for carrier input versus carrier output that the response is non-linear. This results in a considerable distortion of the modulation envelope of carrier wave, which is particularly noticeable on high modulation levels and high carrier input levels. The distortion is due to the inherent property in the operating characteristics of the tubes and not to the improper design of circuit components. Choosing the operating point at a suitable plate current value, the resultant output becomes decidedly unsymmetrical as to the modulation envelope. In order to correct this inherent disadvantage it is proposed, in accordance with this invention, to introduce inverse feed-back of such character which will maintain the average plate current of the tube substantially constant over the audio cycle. In other words, prevent plate current variation at the audio rate of modulation. If plate current variation is permitted, the resulting distortion is equivalent to a partial detection in the radio frequency stages. In radio frequency amplifiers, it is a primary requisite for true amplification that no detection or rectification of the modulation component of the signal shall take place.

One object of my invention is, accordingly, to prevent distortion of the modulation envelope of the carrier wave which otherwise is met with in the use of remote cut-off tubes in radio frequency amplifiers.

Another object of my invention is to prevent distortion of the modulation envelope of the carrier wave by radio frequency amplifiers employing remote cut-off tubes when operating at high modulation levels.

Still another object of my invention is to prevent distortion of the modulation envelope of the carrier wave by radio frequency amplifiers employing remote cut-off tubes when operating at high carrier input voltage levels.

A further object of my invention is to substantially prevent even partial detection of the modulation signal when passing through a radio frequency amplifier employing tubes in the remote cut-off condition.

Other objects of my invention will become apparent upon reading the following description taken in connection with the drawings, in which:

Figure 1 is a general schematic diagram and Fig. 2 a detailed circuit diagram of a carrier current wire transmission system which embodies a radio frequency amplifier employing the principles of my invention; and

Fig. 3 is a plot of curves useful in explaining certain features of my invention.

This application is a continuation-in-part of application Serial No. 349,526 for Two-way radio transmission, filed August 2, 1940, now Patent No. 2,310,060, Feb. 2, 1943, and assigned to the Westinghouse Electric & Manufacturing Company of East Pittsburgh, Pennsylvania.

The system illustrated in Figs. 1 and 2, which is used as illustrative of the employment of my particular invention, is a carrier frequency communication system which utilizes only a single channel for simplex operation.

Systems of the above type may have several communication centers or stations each being equipped with a transmitter and a receiver. Since only a single communication channel is available, the transmitter, as well as the receiver, must operate on the same carrier frequency. This presents a serious problem of preventing interaction between the transmitter and the receiver located at the same station and at the same time each of these must be readily available for operation in quick succession where communication is carried out between two remotely located stations. In other words, when, let us say, at station A the operator is speaking to station B, the transmitter at A must be functioning whereas the receiver at A must be inoperative. On the other hand, at station B the receiver must function and the transmitter must be inoperative. At the next instant, when the operator at B wishes to answer A, the order must be reversed and the receiver at A is to become operative, whereas the transmitter must be silenced, not only with respect to the modulation comprising the speech of the operator at station A, but also the carrier frequency, inasmuch as there can be no two carriers at the same time.

The operation of a system of this type has various other ramifications which will be taken up in detail hereafter. Suffice it to say that heretofore such systems required elaborate switching arrangements in order the communication could be carried on without much loss of time in the same manner as, for example, over a simple telephone line. These switching arrangements employed a considerable number of relays and other mechanical transfer switches to interchange the transmitting and receiving circuits and effect en-

ergization of different elements of the circuits. Mechanical relays have the inherent disadvantage of possessing mechanical inertia. Furthermore, difficulties are caused by moving contacts in chattering and arcing which, in systems of the type herein considered, seriously interfere with smooth operation.

The major switching in prior systems involved the use of transfer switches which often had to be manually operated for going over from transmitter to receiver operation, and vice versa. In such systems both the input and output circuits of the transmitter and the receiver terminated at switch contacts. The necessity of having these circuits alternately connected and broken proved to be a serious disadvantage. This condition was somewhat ameliorated by terminating the circuits in hybrid coils which needed careful and difficult balancing of input and output networks.

The present system has for its primary object automatic simplex operation without any of the above mentioned disadvantages by providing electronic means for automatically conditioning the various circuits for operative or inoperative function as demanded by the normal use of the system.

A particular feature of this system is that the system obviates the necessity of using mechanical switching means in any form.

Another advantage offered by the communication system in accordance with this invention is that the hybrid coils for terminating the circuit are dispensed with and circuits heretofore so terminated can be directly interconnected.

A further feature of primary importance of the system resides in the increased exchange rate of communication over a single channel by providing electronic control circuits having operating time constants less than the syllabic time of human speech.

The system finds particular usefulness in carrier current communication which employs power lines as the medium for conducting the carrier frequency current from one communication center to the other. In such systems single frequency operation is particularly advantageous in that it simplifies the equipment and makes full use of the limited facilities which a power line offers for conducting carrier frequency current. For this reason the system is stated and described as a carrier current system, although no limitation is intended thereby and there is no difference in the general basic organization of the circuits whether the transmitted high frequency energy is carried over wires or is emitted through the ether space.

The power line is indicated by conductors 1, 2 and 3 which may be a direct current line or two-phase or three-phase alternating current. The carrier frequency is superimposed on one pair of lines shown here as 2 and 3 by means of a coupling system employing condensers 4, 5, 6 and 4', 5', 6' in series to minimize the breakdown of the high voltage of the power line. These condensers offer a high impedance to the power frequency and a comparatively low impedance at carrier frequency. In series with condensers 4, 5 and 6 and terminating to ground is a radio frequency reactance 7, and similarly in series with condensers 4', 5' and 6', is a radio frequency reactance 7'. The latter are for the purpose of obtaining a comparatively high impedance to the carrier frequency to be transmitted. A line tuning unit is provided between the coupling circuit and the transmitter, shown here in block

form, to match the line impedance with the output circuit of the transmitter. The transmitter and receiver are shown in one block diagram, since this invention permits permanent interconnection of these units as will be seen later, and both are permanently tied in with the line tuning unit. Blocks T and T' indicate telephone apparatus connected to the transmitter and receiver. The other units of Fig. 1, each representing a communication center, are identical with the one just described. Similar components thereof are marked with identical reference characters.

Referring to Fig. 2, the essential circuit elements of a complete transmitter and receiver are shown here in a simplified form. The novel electronic control circuits may be applied to any type of receiver and transmitter. For the purpose of simplicity the transmitter circuit components include all the essential elements for a complete operative unit. Similarly, in the receiver a simple tuned radio frequency circuit was selected. There is no limitation intended in showing these circuits which can be modified as circumstances may demand to have more selectivity by including other tuned circuits or by employing a superheterodyne type receiver. Similarly, in the transmitter other types of oscillators or modulators well known in the art may be employed to obtain any desired transmission characteristics.

Provision is made for the system to operate as follows:

1. When signals are being transmitted to render the receiver inoperative to full transmitter output voltage prior to and during transmission of carrier.

2. Release the receiver block after carrier transmission has ceased yet soon enough to receive the beginning of the next part of the incoming conversation.

3. Rendering the transmitter inoperative by means of the received signal prior to its arrival at the receiving instrument and during the reception interval.

4. Release of transmitter blocking after reception has terminated but soon enough to prevent loss of any of the ensuing conversation.

Other features of the operation whereby the above requirements may be fulfilled are the time sequence characteristic of the control system and a level sequence providing an additional reduction in the time delay of action. This will be fully described in connection with the circuit shown in Fig. 2.

5. The components enclosed by one rectangle in dotted lines represent the receiving apparatus, those in another square the signal frequency transmission circuit and part of the control circuit of the transmitter, whereas those in the third square, the main components of the transmitter. A simple telephone handset 8 provides for transmission and reception of signals and is connected by a telephone line comprising conductors 9 and 10 in series with the customary microphone voltage source represented by the battery 11 to the input circuit of the transmitter and the output circuit of the receiver. These two circuits therefore are permanently tied together by the telephone lines 9 and 10. Similarly, the input circuit of the receiver and the output circuit of the transmitter are permanently tied together by conductors 11 and 12 which ultimately terminate in the line tuning unit shown in Fig.

1. It may be mentioned here prior to discussing the circuit that a permanent interconnection of

this type could not be effected heretofore because of the interaction that a transmitter would have on a receiver, and vice versa, resulting in a serious oscillation of the entire system referred to in telephone practice as "singing." A number of relays and switches had to be used to transfer the telephone lines 9 and 10 and the output-input conductors 11, 12 to the circuits under operation.

The receiver includes in a conventional circuit arrangement the vacuum tubes 13, 14 and 15 in which the vacuum tube 13 performs the function of a carrier frequency amplifier having its input circuit between grid 16 and cathode 17 connected to the conductors 11 and 12 by a suitable coupling circuit.

The present invention in distortionless radio frequency amplifiers is embodied in the tube 13 and comprises the combination of resistive, capacitive and inductive bypass elements 25, 26 and 27 in the cathode circuit of the tube 13. The tube 13 receives modulated carrier input from the transformer 18 which is tuned by condenser 19 and a series tuned circuit comprising the primary coil 20 of the transformer 18, a series capacity 21 and a secondary winding 22 of the input transformer 23. The primary winding 24 of the latter connects directly with the conductors 11 and 12. The vacuum tube 13 is shown to be a pentode voltage amplifier deriving operating potentials from the source shown here by the battery 28.

Referring to the above-mentioned network in the cathode lead, the inductance 27 is a reactor which has a comparatively high impedance at the modulation frequencies, whereas the ohmic resistance thereof is of such value which will provide a suitable voltage drop for the grid bias. I have found it desirable that the inductance 27 be of the iron-core type to readily provide the high inductance required for most service. In other words, the grid bias is obtained from the inherent ohmic resistance of the choke coil 27. If the choke coil does not have an ohmic resistance of suitably high value, a resistance may be inserted in series therewith. On the other hand, if the ohmic value of the inductance 27 is too high, resulting in excessive bias for the grid of the tube, a compensating battery may be included between ground and the grid return so poled as to provide a positive bias to counteract the negative bias produced by the high ohmic resistance. Let us assume that we have the proper inductance 27 with the necessary ohmic resistance value so that no auxiliary bias battery is needed. In parallel with the inductance 27 we have the resistor 25 which is chosen to be of a value slightly lower than the reactance of the inductance at the lowest modulation frequency. The condenser 26 in parallel with the above described elements is of such value as to effectively bypass the carrier frequency but offer a higher impedance to the modulation frequency than the resistor 25. It is important that these values shall be carefully chosen in order to obtain the improved operation of the amplifier. Best results may be obtained if the network comprising the resistor 25, the inductance 27, and the condenser 26 is substantially resistive over the audio frequency range.

Describing the operation of the amplifier, reference is to be had to Fig. 3 which illustrates by means of curves the carrier output with respect to carrier input voltage and also the variation of plate current in a conventional amplifier. Experimental investigations showed that if the plate

current is maintained substantially constant the carrier output response curve loses its undesirable curvature and becomes very nearly linear, within a wide range of carrier input voltages. The problem, therefore, is to find means whereby the plate current may be effectively held constant over the audio cycle. In other words, the average plate current within the modulation rate of change of voltage of the carrier should be held constant. Referring again to Fig. 2, this is accomplished by the inverse feedback circuit in the cathode of the amplifier tube in the following manner:

The resistor 25, being a non-reactive element, determines the instantaneous negative grid voltage and any change of plate current is counteracted by the bias resulting from the voltage drop across the resistor 25 due to plate current. The function of the inductance 27 as stated before is to have a high reactance at audio frequencies acting at the same time as a shunt with respect to the effective direct current resistance. The capacitor 26, on the other hand, will not influence the direct current resistance value of the combination but will function as a low impedance shunt for the carrier frequency. A better understanding may be had if we again bear in mind that the object is to derive a degenerative feedback voltage only from the modulation frequency component of the signal. Consequently, a high impedance must be provided for the modulation frequency and a low impedance for the carrier frequency in the cathode circuit. The high value of the resistance 25 at any frequency provides the necessary feedback voltage whereas the condenser provides the low impedance at carrier frequency. The function of the inductance 27 is to form a convenient direct current bypass for the conventional circuit in which the operating point is determined solely by the voltage drop in the cathode circuit. Without the inductance 27, the required high resistance for the resistor would adversely affect the operating voltages. In this case a positive initial bias voltage will be necessary for the grid circuit. By placing the inductance 27 in shunt with the resistor 25, the ohmic value of this inductance is the main factor in determining the operating bias voltage. On the other hand, at the modulation frequencies the high impedance of the shunt 27 will not affect the net resistance in the cathode circuit for developing the required degenerative feedback voltage.

Returning to the detailed description of the carrier current communication system of Figs. 1 and 2, batteries were chosen to indicate the various voltage sources wherefrom static operating potentials are derived for the different tubes. In this manner the drawings and the explanation of the operation of the system can be greatly simplified. It is to be understood, of course, that no limitation is intended thereby, and in present-day practice all these sources may be replaced by suitable rectified alternating current power supplies. For the same reason the filament circuit of the tubes has been omitted for it is well understood that these tubes require heating currents which may be derived from any suitable source.

In continuing with the description, the battery 28 has its negative terminal connected to the ground terminal side of the cathode 17, and at an intermediate point suitable voltage is tapped off for the screen grid electrode 29. The anode 30 is connected to the positive terminal of the battery 28 in series with primary winding 31 of the carrier frequency transformer 32 which is

tuned by condenser 38. This forms the output circuit of the tube 13. The secondary winding 34 of transformer 32 is connected to a demodulator comprising the duodiode tube 14 having anodes 35 and 36 which are interconnected with one terminal of the secondary winding 34. The latter is also tuned by condenser 37. The cathode 38 of this tube is connected to the junction point of resistors 39 and 39'. The former is the load resistance of one diode section, its other terminal being connected to the low potential side of the secondary winding 34 of transformer 32 by conductor 40 and also to the control grid 41 of the vacuum tube 15 through conductor 42. A condenser 43 connected between conductors 40 and 39' and in conjunction with resistor 39' serves as a modulation frequency filter for the input circuit of tube 15 as will be described in connection with the operation of the system. The vacuum tube 15 is essentially a direct current amplifier and performs the function of the conventional automatic volume control tube in receiving circuits. The cathode 44 thereof is connected to the common terminal of batteries 45 and 46. The latter provides a source of operating voltage supplying the screen grid 47 and the anode 48 which has a load resistance 49 by-passed by a condenser 50, whereas the former supplies bias potential being effectively connected between grid 41 and cathode 44. The anode 48 connects also through conductor 51 to the cathode 52 of control tube 53. This will be fully described in connection with the description of the control circuit. The other portion of the duodiode tube 14, including cathode 54, may be referred to as the signal diode or detector of the system feeding the output amplifier tube 55. The output connection includes between cathode 54 and conductor 40 the load resistors 57 and 58 in series. The junction point thereof is connected to the grid 56 of tube 55 through a coupling network including resistor 59, coupling capacity 60 and filter capacity 61 connected between the junction point of resistor 59 and condenser 60 and conductor 40.

Between the cathode 62 and the anode 63 of the output amplifier tube 55 is the output circuit comprising the primary winding 64 of the output transformer, the secondary winding 65 of which connects to conductors 9 and 10 and the anode voltage source in the form of battery 66. Operating bias voltage for the input circuit of the tube 55 is obtained from the battery 67 through control tube load resistor 68 which is by-passed for signal frequencies by the condenser 69 and grid resistor 70, the junction point of the two last-mentioned resistors being connected to the anode 71 of control tube 72.

The control circuit includes vacuum tubes 53 and 72, mentioned before, and vacuum tube 73. The anode circuit of the vacuum tube 72 was described in part comprising the anode 74 and load resistance 68. The operating source therefore is the other half of the battery 66, the negative terminal of which is connected to the cathode 74 which is also at ground potential. The input to the control tube includes the control grid 75, resistor 76 and bias source battery 77, returning to the cathode 74. The grid 75 is also coupled directly to the output circuit of tube 73. This includes the resistor 78 and the anode 79 of the tube 73 in series with resistor 76, operating source battery 80, returning to the cathode 81. Resistors 76 and 78 are thereby in series and bypassed by the condenser 82. A suitable voltage tap of the battery 80 supplies the screen grid

electrode 83 of tube 73. The input circuit of the control tube 73 includes the grid 84, conductor 85 and also the secondary winding 86 of the radio frequency transformer 32, returning through conductor 40 and conductor 86 to the bias source battery 87 and cathode 81. The anode 79 is also a point of interlinkage between receiver and transmitter, the conductor 88 being connected thereto terminating at the positive terminal of the bias supply battery 90 of the modulation frequency amplifier of the transmitter.

Another interconnection is provided between receiver and transmitter by the conductor 91 which connects the cathode 92 of tube 53 and the anode of one of the control tubes of the transmitter which will be described later. The control tube 53 is a duodiode rectifier providing by its space current a path to the input circuit of the tube 13 for the automatic volume control derived from tube 15 and for control derived from the transmitter through the conductor 91. The anodes 93 and 93' thereof are interconnected and terminate at the junction point of the grid return circuit of tube 13 and resistor 95 and by-pass condenser 96 and bias source battery 98 which supplied the minimum operating bias for the grid 16 of tube 13.

The transmitter circuit comprises the following conventional components. The first signal frequency amplifying stage including vacuum tube 100 followed by modulating stage having vacuum tube 101, the oscillation generator including vacuum tube 102 and the final output amplifier stage including vacuum tube 103. The other tubes represent the control circuit and will be described later.

Feeding the input amplifier is the coupling transformer 104, the primary winding 105 of which connects to the conductors 9 and 10. The secondary winding 106 forms the input circuit of the tube 100 between grid 107 and cathode 108 in series with the bias source battery 109. Anode and screen grid potentials are derived from the battery 110. The screen grid electrode 111 is bypassed by condenser 112. The anode circuit includes coupling transformer 113, the primary winding 114 of which connects from the positive terminal of the battery to the anode 115 of the tube 100. The secondary winding 116 forms the input circuit to amplifying tube 101 being connected to the grid 117 thereof at one terminal, whereas the return terminal connects through the bias supply source battery 90 to conductor 88 which terminates at the anode 79 of the control tube 73. The output circuit of modulator tube 101 includes the anode 118, the primary winding 119 of coupling transmitter 120, the anode potential source battery 121 and the cathode 122. The secondary winding 123 of the transformer 120 feeds into the primary winding 124 of the modulation transformer 125. The secondary winding 126 thereof is in the input circuit of the final amplifying tube 103 comprising the grid 127, resistor 128, the secondary winding 126 and the grid bias battery 129 in series. The positive terminal thereof is connected to ground completing the circuit to the cathode 130 of the tube 103 which also connects to ground. The output circuit of the amplifier tube 103 includes in series between cathode 130 and anode 131 the plate potential source battery 132 and the primary winding 133 of the output transformer 134. A suitable tap of the battery 132 connects to the screen grid electrode 135 which is bypassed by condenser

136. The secondary winding 137 of the output transformer 131 connects to the conductors 11 and 12.

The oscillator stage comprises a screen grid type vacuum tube 102 in a conventional feedback coupling. The cathode 138 thereof is connected to ground and the grid circuit includes grid electrode 139, grid load resistor 140 terminating to ground. The anode circuit includes the supply source battery 141, radio frequency choke coil 142 and the anode 143 of the tube 102. The coupling between anode and grid circuit is effected by the variable inductance 144, one terminal of which connects to the grid 139 and the other in series with condenser 145 to the anode 143. The oscillator circuit includes also series condenser 146 between grid 139 and ground and voltage distribution condensers 147 and 148 in series between ground and the high potential terminal of the variable inductance 144. The junction point between condensers 147 and 148 is utilized in coupling the carrier frequency energy to the grid 127 of the final amplifying tube 103 through coupling capacity 149 and conductor 150.

The control circuit has two main branches, each operating on the rectified component of the signal frequency energy which is derived from two diode rectifiers 151 and 152 which are energized from the amplifier tube 153. One of the control tubes 154 operates from two energizing sources, one of which is the output of the diode 151, and the other the output of the oscillator 102, whereas the other control tube 155 operates from the output of the diode 152.

Following the circuit, the amplifier tube 153 is energized simultaneously with amplifier tube 101 from the secondary winding 116 of the coupling transformer 113 in that the grid electrode 156 thereof connects to the grid 117 of the tube 101, and the cathode 157 to the cathode 122. The source 121 is also utilized for anode potential through the primary winding 158 of the transformer 159 connecting to the anode 160. The transformer 159 has two secondary windings 161 and 162. The former in a full wave rectifying arrangement connects at both terminals to the anodes 163 and 163' of the diode 151 and the midtap of this winding is returned to the cathode 164 through load resistance potentiometer 165. The unidirectional voltage output is taken from the potentiometer between the rider 166 and the cathode terminal. This output is fed to the grid 167 of the control tube 154 in series with radio frequency choke coil 168 and resistor 169, the cathode 170 being connected to the midtap terminal of the potentiometer 165 through bias battery 171. Anode potential for the control tube 154 is obtained from the battery 172, the positive terminal of which is grounded and the negative connected to the cathode 170. Screen grid voltage is taken from a suitable tap to the screen grid electrode 173 by-passed by condenser 174. The anode 175 connects to the conductor 91 previously mentioned in connection with the description of the receiver. The anode circuit of the control tube 154 may be traced through the conductor 91, the space current path of the diode 53, resistor 95, battery 96 to ground which is the positive terminal also of the battery 172.

The second diode 152 is similarly energized from the transformer 159, the secondary winding 162 thereof being connected between anodes 176 and 176'. The midtap in series with load resistance potentiometer 177 connects to the cathode

178. The load resistance 177 is paralleled by condenser 179. The rider 180 of the potentiometer 177 connects to the control grid 181 of the control tube 155, returning to the cathode 182 thereof in series with grid bias battery 183. Anode potential for the tube 155 is derived from the battery 184, the negative terminal of which connects to the cathode 182, whereas the positive terminal is in series with load resistance 185 and the anode 186. Screen grid voltage is derived from a suitable tap which connects to the screen grid electrode 187. A portion of the battery voltage is utilized also to supply operating voltage to the screen grid electrode 98 of the oscillator tube 102. This is accomplished by grounding a suitable point of the battery 184 and tying the screen grid electrode 98 to the anode 186 through conductor 188. This completes the description of the circuit. The various phases of the operation 20 of the receiver and transmitter as a complete unit shall now be described.

Every communication center of the system includes a complete assembly of receiver, transmitter and control circuit as shown in Fig. 2, 25 forming thereby an operating unit in the chain supplied by the communication channel. Let us assume that it is desired to send a message from this station and the microphone of the handset 8 receives voice frequencies. The audio-frequency energy is fed through the transformer 104 and is amplified by vacuum tube 100, and also further amplified by vacuum tube 101, the output of which is delivered to transformer 125. This energy then modulates the carrier frequency 30 which is impressed on the grid 127 of the tube 103 through the condenser 149. The energy is then delivered by conductors 12 and 11 which, as shown in Fig. 1, connect to the line tuning unit through which it is delivered to the power lines 2 and 3.

In addition to this function, audio-frequency energy is also delivered from the transformer 113 to the grid 156 of control amplifier tube 153. The output thereof is delivered to transformer 159 45 being rectified by both diodes 151 and 152. The output voltage of diode 151 appears across potentiometer 165 and is applied to the grid 167 of the tube 154. The latter is normally biased to plate current cutoff by the battery 171. Simultaneously the output voltage of the diode 152 appears across potentiometer 177 and is applied to the grid 181 of control tube 155. The latter is biased by the battery 183 for normal plate current at no signal conditions. The voltage between cathode 182 and ground is so adjusted that it is greater than the voltage drop of the tube 155 through load resistance 185 thereby applying a slightly negative voltage to the screen grid 98 of the oscillator 102 with respect to its cathode 138 which prevents the oscillator tube from generating carrier frequency energy. However, as soon as signal reaches the transformer 159 the voltage appearing at 177 will be more negative and cuts off the anode current of the tube 155. Hence the potential between the anode 186 and ground becomes positive and the screen grid 98 will be normally energized, permitting the tube 102 to oscillate and thereby produce carrier frequency energy.

Prior to discussing the function of the other control tube 154, reviewing the operation of control tube 155, it is seen that normally the oscillator tube 102 has negative potential on the screen electrode 98 and thereby is prevented from oscil-

lation. The signal amplifier tubes, on the other hand, are in a stand-by condition, and as soon as signal frequency appears in the modulation circuit the negative bias is removed from the screen electrode and the oscillator becomes instantly operative. As soon as there is no audio-frequency signal, the oscillator again becomes inoperative. The time sequence of operation is governed by the constants of the control circuit, and it is important that these constants be of a predetermined character. This will be further explained as the operation of the circuit is unfolded.

Simultaneously with the energization of the oscillator to an operative state, the control tube 154 will receive bias voltage on its grid 167 from the output of the diode 151. This tube is normally biased to plate current cutoff by the battery 171. The control voltage produced by the diode 151 will oppose the voltage of the battery 171, permitting the flow of anode current of the tube 154 which flows from ground through battery 96, resistor 95, diode 53 and anode 175, returning to the negative side of the battery 172. The voltage produced by the current flow across the resistor 95 applies sufficient negative bias to the control grid 16 of tube 13 to render the input amplifier stage of the receiver inoperative to the full voltage of the output of the transmitter which will appear across the primary winding 24 due to the fact that it is connected also across conductors 11 and 12.

The time required to block the receiver to inoperative condition is a function of the values of resistor 95, condenser 94 and the plate resistance of the tube 154. The time for actuating the carrier at the tube 103 is a function of the values of the capacity 179, resistor 177, capacity 99 and resistance of the screen grid 98 to the cathode 138. The values of the above-mentioned components are so proportioned that the receiver is blocked to inoperative condition prior to the beginning of generation of radio frequency energy by the tube 102.

Recapitulating briefly the operation, as soon as the microphone is energized, signal frequency currents will appear in the modulator amplifier stage, and will also produce through the control tube 153 and diodes 151 and 152 two sets of control voltages. One is utilized to trigger the oscillator tube into action, the latter being normally in a stage of inoperativeness, and the other voltage is utilized to cut off the first amplifying stage of the receiver which is normally in a receptive state.

The receiving functions operate as follows. Upon impression of carrier frequency voltage on the input terminals of the primary winding 24 of transformer 23, the signal is amplified through the first stage including amplifier tube 13, and is delivered to the demodulator tube 14 and also through the conductor 85 to the grid 84 of the control tube 73. The signal from the demodulator tube is impressed on the grid 56 of the amplifier tube 55 through the capacity from the load resistances 57 and 58 of the diode section comprising anode 35 and cathode 54. The other diode section comprising anode 36 and cathode 38 produces a unidirectional voltage which is fed through the resistor 39 by-passed by capacity 48 to the grid 41 of the automatic volume control tube 15. The operation of this tube is in the conventional manner in that the increased signal voltage produces an increase of positive voltage

on the grid 41 causing plate current which is in such direction as to apply a negative voltage to the cathode 52 and thereby control the bias on the control grid 16 of the first amplifier tube 13. As stated before, the carrier frequency is also impressed on the grid 84 of tube 73. The latter is normally biased to cutoff point by the battery 87. The impressed signal causes plate current flow from the anode potential battery 80 through the resistors 76 and 78. The other control tube 12 is biased by the battery 11 to normal plate current flow which, while it is maintained, is in such direction through resistor 68 as to bias the output stage of the receiver, namely, the grid 56 of tube 55 to cutoff condition. Upon carrier frequency appearing on the grid 84 of tube 73, plate current conduction is initiated which, flowing through the resistor 76, will deliver additional negative bias to tube 72 initiating cutoff condition, thereby removing the negative bias on the grid 56 caused by plate current through resistor 68. Thus, we have an inoperative receiver as to its final output stage until such time as a carrier signal either modulated or unmodulated is applied to the vacuum tube 73. The release of current through resistors 76 and 78 is also in such a direction and magnitude as to apply cutoff bias to vacuum tubes 101 and 153. The time required to cut off tubes 101 and 153 is a function of the values of capacity 82, and the anode impedance of tube 73. The time required to release the cutoff bias from vacuum tube 55 in the output stage of the receiver for delivery of signal to the telephone receiver 8 is a function of the values of resistor 68 and capacity 69. The values of the above-mentioned components are such that the vacuum tubes 101 and 153 are cut off to non-operation prior to the removal of cutoff bias holding the tube 55 produced by current flow through the resistor 68.

It is seen from the above that the receiver is blocked to inoperative condition prior to and during the generation of radio frequency energy from the transmitter. The latter condition is assured by the coupling of the oscillator grid 139 to the grid 167 of control tube 154 by means of the capacity 97 which connects to the junction point of the resistor 169 and choke coil 168, thereby some of the carrier is fed to the control tube 154 in order that the receiver shall be blocked as long as carrier is generated by the transmitter. Upon cessation of signal frequency, that is, audio-frequency the carrier stops after which the receiver is restored to operative condition upon the discharge of capacitor 94 through resistor 95. The receiver now is in a stand-by condition, and upon impression of a received signal the actuation of carrier by the transmitter is prevented by blocking off the tubes 101 and 153 prior to the delivery of the received signal to the telephone 8 from the receiver. Upon cessation of received carrier the tube 55 will be blocked to inoperative condition by the tube 72 prior to or simultaneously with the restoration of normal operating bias to the tubes 101 and 153.

In addition to the timing sequence described above, the principle of level sequence is also applied for the purpose of improving operation characteristics. For example, the signal frequency gain from the telephone to the grid 167 of tube 154 is great enough to block the receiver to inoperative condition at a level equal to or below that required to actuate carrier. Furthermore, tubes 101 and 153 are blocked to an inoper-

ative condition at a signal level equal to or below that required to actuate the final amplifier stage of the receiver that is tube 55. If the precautions of timing and sequence are applied as described above, it becomes possible to obtain automatic operation controlled entirely by the normal conversational speech, that is, at less than syllabic time. A loss of time from the initiation of a speech tone at the input of the transmitter and the delivery of this tone at the output of the distant receiver can be made less than ten milliseconds. This value has been found by experiment to be entirely negligible in its adverse effects to the utility of the system.

I claim as my invention:

1. An amplifier comprising a tube having anode, cathode and at least one control electrode, means for biasing said electrodes for operation on a portion of the output characteristic of said tube which is remote from the cut-off point, an inductance, a capacitor and a resistor connected in parallel with each other and carrying the entire cathode current of said tube, a control electrode circuit interconnecting the control electrode with the terminus of said parallel circuit elements which is remote from said cathode, and an output circuit connected between the anode and said terminus.

2. An amplifier comprising a tube having anode, cathode and at least one control electrode, means for biasing said electrodes for operation on a portion of the output characteristic of said tube which is remote from the cut-off point, an inductance, a capacitor and a resistor connected in parallel with each other and carrying the entire cathode current of said tube, a control electrode circuit interconnecting the control electrode with the terminus of said parallel circuit elements which is remote from said cathode, and an output circuit connected between the anode and said terminus.

3. An amplifier comprising a tube having anode, cathode and at least one control electrode, means for biasing said electrodes for operation on a portion of the output characteristic of said tube which is remote from the cut-off point, an inductance, a capacitor and a resistor connected in parallel with each other and carrying the entire cathode current of said tube, and an output circuit connected between the anode and said terminus.

4. An amplifier comprising a tube for modulated

carrier current having an anode, cathode and at least one control electrode, an inductance which has an impedance high at said modulation frequency, a capacitor and a resistor connected in parallel with each other in the cathode lead of said tube, a control electrode circuit interconnecting the control electrode with the terminus of said parallel circuit elements which is remote from said cathode, and an output circuit connected between the anode and said terminus.

5. An amplifier comprising a tube for modulated carrier current having an anode, cathode and at least one control electrode, an inductance which has an impedance high at said modulation frequency, a capacitor and a resistor connected in parallel with each other in the cathode lead of said tube, a control electrode circuit interconnecting the control electrode with the terminus of said parallel circuit elements which is remote from said cathode, and an output circuit connected between the anode and said terminus.

6. An amplifier comprising a tube for modulated carrier current having an anode, cathode and at least one control electrode, an inductance which has an impedance high at said modulation frequency, a capacitor and a resistor connected in parallel with each other in the cathode lead of said tube, said resistor having an impedance slightly lower than that of said inductance, a control electrode circuit interconnecting the control electrode with the terminus of said parallel circuit elements which is remote from said cathode, and an output circuit connected between the anode and said terminus.

15 7. An amplifier comprising a tube for modulated carrier current having an anode, cathode and at least one control electrode, an inductance which has an impedance high at said modulation frequency, a capacitor and a resistor connected in parallel with each other in the cathode lead of said tube, said resistor having an impedance slightly lower than that of said inductance, a control electrode circuit interconnecting the control electrode with the terminus of said parallel circuit elements which is remote from said cathode, and an output circuit connected between the anode and said terminus.

20 8. An amplifier comprising a tube for modulated carrier current having an anode, cathode and at least one control electrode, an inductance which has an impedance high at said modulation frequency, a capacitor and a resistor connected in parallel with each other in the cathode lead of said tube, said resistor having an impedance slightly lower than that of said inductance, a control electrode circuit interconnecting the control electrode with the terminus of said parallel circuit elements which is remote from said cathode, and an output circuit connected between the anode and said terminus.

25 9. An amplifier comprising a tube for modulated carrier current having an anode, cathode and at least one control electrode, an inductance which has an impedance high at said modulation frequency, a capacitor and a resistor connected in parallel with each other in the cathode lead of said tube, said resistor having an impedance slightly lower than that of said inductance, a control electrode circuit interconnecting the control electrode with the terminus of said parallel circuit elements which is remote from said cathode, and an output circuit connected between the anode and said terminus.

30 10. An amplifier comprising a tube for modulated carrier current having an anode, cathode and at least one control electrode, an inductance which has an impedance high at said modulation frequency, a capacitor and a resistor connected in parallel with each other in the cathode lead of said tube, said resistor having an impedance slightly lower than that of said inductance, a control electrode circuit interconnecting the control electrode with the terminus of said parallel circuit elements which is remote from said cathode, and an output circuit connected between the anode and said terminus.

35 11. An amplifier comprising a tube for modulated carrier current having an anode, cathode and at least one control electrode, an inductance which has an impedance high at said modulation frequency, a capacitor and a resistor connected in parallel with each other in the cathode lead of said tube, said resistor having an impedance slightly lower than that of said inductance, a control electrode circuit interconnecting the control electrode with the terminus of said parallel circuit elements which is remote from said cathode, and an output circuit connected between the anode and said terminus.

40 12. An amplifier comprising a tube for modulated carrier current having an anode, cathode and at least one control electrode, an inductance which has an impedance high at said modulation frequency, a capacitor and a resistor connected in parallel with each other in the cathode lead of said tube, said capacitor and said resistor each having an impedance which is high at said modulation frequency, a control electrode circuit interconnecting the control electrode with the terminus of said parallel circuit elements which is remote from said cathode, and an output circuit connected between the anode and said terminus.

45 13. An amplifier comprising a tube for modulated carrier current having an anode, cathode and at least one control electrode, an inductance which has an impedance high at said modulation frequency, a capacitor and a resistor connected in parallel with each other in the cathode lead of said tube, said capacitor and said resistor each having an impedance which is high at said modulation frequency, a control electrode circuit interconnecting the control electrode with the terminus of said parallel circuit elements which is remote from said cathode, and an output circuit connected between the anode and said terminus.
